(57) **CLAIM**

The ornamental design for a vehicle control panel, as shown and described.

DESCRIPTION

FIG. 1 is a perspective view of a vehicle control panel showing my new design; and,

FIG. 2 is a front view thereof.

The heavy jagged broken line denotes a boundary of the claimed design and forms no part thereof. The broken line showings of the numbers, icons, and other indicia on the panel depict environmental subject matter and form no part of the claimed design.
